UNITED STATES PATENT OFFICE.

EUGENE DESFOSSÉ, OF PARIS, FRANCE.

DESIGN FOR AN ARTICLE OF MANUFACTURE.

48,775.

Specification for Design.

Patented Mar. 28, 1916.

Application filed December 28, 1915. Serial No. 69,299. Term of patent 7 years.

To all whom it may concern:

Be it known that I, EUGENE DESFOSSÉ, a citizen of the Republic of France, and a resident of Paris, in said Republic of France, have invented a certain new, original, and ornamental Design for an Article of Manufacture, of which the following is a specification, reference being had to the accom-

panying drawing, forming part thereof, in which the figure is a face view of a portion of an article of manufacture, illustrating my new design.

I claim:—

The ornamental design for an article of manufacture, substantially as shown.

E. DESFOSSÉ.
